Isidor Tornberg, Plainfield, N. J., assignor to
 Wood Newspaper Machinery Corporation, New
 York, N. Y., a corporation of Virginia

Application June 9, 1936, Serial No. 84,244

6 Claims. (Cl. 270—5)

This invention relates to the application of one or more color printing units to one or more black and white printing unit so that color can be provided in the daily run of newspapers with the least possible expense and difficulty in production than has heretofore been necessary.

The principal objects of the invention are to provide an inexpensive equipment for placing pages carrying color in desired position whenever necessary with reference to the other pages of a newspaper; to provide a compact arrangement of printing cylinders for applying as many as four extra colors to a single web and still retain the desired flexibility of using part of the unit for printing on one web while another part prints on a second web; to provide a means for leading the web not only above and below the color units but in between the two impression cylinders thereof, to provide an arrangement which permits the placing of color on any of a plurality of webs and furnishes an easy arrangement for leading the sheets into the folder; to provide a convenient drive whereby the shifting of a single gear on each impression cylinder of the color press will reverse the printing couple so that the couples may be driven both in one direction, or in the other direction, or in opposing directions, as desired, to provide compact gearing so that in printing four colors there is a minimum difficulty experienced in maintaining register between the four printing cylinders; to provide in addition a certain number of black and white decks and their reels with an extra reel from which the web is led through one of the decks and other webs through other decks, two webs being led through one deck on which web each is printed on one side and then through two color decks on which each may be printed in either one or two colors, on the opposite side in the space required for an extra black and white deck.

Other objects and advantages of the invention will appear hereinafter.

Reference is to be had to the accompanying drawings, in which

Fig. 1 is a diagrammatic side view of an arrangement of four black and white decks with a folder and a color unit, capable of printing in one or more colors, arranged in accordance with this with this invention;

Fig. 2 is a view illustrating the same machinery with four additional colors adapted to be applied to the outside pages of a newspaper;

Fig. 3 is a similar view showing an arrangement

of leads whereby two additional colors can be placed on one side of each of two webs;

Fig. 4 is a similar view showing the web leads with two additional colors applied to each side of one web, the other webs being led directly to the folder;

Fig. 5 is a view of a similar character showing this invention employed in a machine in which there are four black and white decks with four reels therefor and an additional reel beyond the end of them, the web from which leads through one of said decks and directly to the folder while two webs are led through two other decks directly to the folder and the webs from two of the reels are led through another deck and to the color unit where they are printed upon on the other side in either one or two colors;

Fig. 6 is an end view of the driving arrangement for the color unit;

Fig. 7 shows one combination of gearing in which the top sides of the impression cylinders are running toward each other;

Fig. 8 shows the opposite combination where the top sides of the impression cylinders are running away from each other;

Fig. 9 shows a combination where both impression cylinders turn to the left as viewed from the top, and

Fig. 10 shows a combination where both impression cylinders turn to the right as viewed from the top.

A well known type of black and white printing decks A, B, C and D are shown arranged in horizontal alignment in Fig. 1. Each unit, of course, has a plate cylinder 1 and impression cylinder 2 and they are shown as perfecting presses, though this is not strictly essential. A corresponding number of reels A', B', C' and D' represents the usual means for supplying webs to the said black and white decks. A color unit F is shown above these decks. It includes two separated impression cylinders 3 and 4 and in this instance four plate cylinders 5, 6, 7 and 8 and suitable ink motions 9, 10, 11 and 12. The ink motions, as indicated, are mounted in retractile or movable carriages, not shown. Preferably two ink motions are mounted on each carriage. The two ink motions 9 and 10 one on carriage are indicated in Fig. 1 as being in operative position while the ink motions 11 and 12 on another carriage are shown as backed away to permit plates to be placed on, or removed from, the plate cylinders 7 and 8.

While the impression cylinders 3 and 4 are relatively close together there is sufficient clear-

ance provided between them through which webs, as for example W^2 and W^3 may be led. It is obvious that no printing is done on these two webs when they are led between the impression cylinders, as shown. The purpose is merely to permit the placement in the desired location of other webs which are being printed. After being printed on in black, preferably, by the units A, B, C and D, these four webs are led over a customary series of guide rolls, into or between the color units and around additional guide rollers, over a drag roll 13 and into a folder E, which is indicated diagrammatically. It will be obvious that the webs W' and W^4 , after being printed on both sides in black in decks A and D, are led through the two color presses and each one is printed in one or two colors on one side.

A horizontal drive shaft is represented diagrammatically by a central line 14. The usual type of bevel gears 15 and 16, vertical shaft 17 and bevel gears 18 and 19 are used as being shown to transmit power to an intermediate shaft which can be employed to drive the deck B. The decks A and D may be driven in a similar manner.

On the shaft 14 is a similar bevel gear 20 meshing with a bevel gear 21 on a vertical shaft 22. Bevel gears 23 and 24 serve as a similar driving arrangement for the deck C. This vertical shaft 20 is adapted to be extended to drive the color unit F. Bevel gears 23 and 24 (see Fig. 6) are secured to the shaft 22 and mesh with bevel gears 25 and 26 respectively, the latter two gears being carried on shafts 27 and 28. Intermediate gears 29 and 30 are secured to the shafts 27 and 28 respectively and mesh with gears 31 and 32 as desired. These last two gears are slidably splined to the impression cylinders 4 and 3 respectively so that they can be moved axially and drive these two cylinders. In the case of the intermediate gear 30, on the shaft 28, it can mesh with the gear 32 on the cylinder 3 in the position shown in Fig. 7 but can also mesh with the gear 31. Thus, it will be seen that a reversible drive may be provided for the impression cylinders 3 and 4. This driving arrangement provides a very flexible device which may be used to drive the impression cylinders 3 and 4 in the various combinations shown in Figs. 7 to 10.

In Fig. 5 the invention is shown in a form in which four black and white decks G, H, I, J, corresponding to the decks A, B, C and D in Fig. 1, are shown with four reels G', H', I' and J'. To this is added an extra reel R'.

The web W^5 from the reel R' is led through the deck G and the web W^6 is led through the deck H. The web W^7 is led through one printing couple 35-36 of the deck I and then to one portion of the color unit F around the impression cylinder 4 where it is printed on the other side of the web by two plate cylinders 7 and 8 or any number of them to print in one or two colors thereon. This gives one color on one side of the web W^7 and one or two colors on the other side.

In a similar manner the web W^8 is led through the other couple 33-34 of the deck I and then around the impression cylinder 3 of the color unit F when it may receive two colors from the plate cylinders 5 and 6 on the opposite side of the web. The web W^9 is led through the deck J.

It will be obvious that, with the four black and white decks and one color deck as constructed with the two parts of the color deck separated from each other, webs may be printed on both sides with the possibility of two of the webs carrying an extra color on one side. This is the

equivalent to providing an extra black and white deck and shows a new and useful arrangement for the combination of black and white and color decks.

If it is desired to place four additional colors 5 besides the black on the outside page of a newspaper the arrangement as shown in Fig. 2 may be used. The driving connection in this case can be the same as that shown in Fig. 10.

In Fig. 3 an arrangement is shown where two 10 additional colors are added to one side of each of the two central webs W^3 and W^4 as folded in the folder E. The driving arrangement of the impression cylinders 3 and 4 corresponds to that shown in Fig. 7 which does not require further 15 explanation.

In Fig. 4 is shown an arrangement whereby two additional colors are added to each side of the outside sheet (Fig. 1) folded in the product at the folder E. In this particular case the driving arrangement is similar to that shown in Fig. 8 which also can be understood from the description already made of Fig. 7.

Only a few of the many arrangements possible are shown but a new and useful arrangement is 25 employed whereby additional colors may be applied to the webs substantially at will and a simple, inexpensive and compact arrangement is shown for interweaving these color carrying webs as desired. 30

Having thus described my invention and the advantages thereof, I do not wish to be limited to the details herein disclosed, otherwise than as set forth in the claims, but what I claim is:

1. The combination with a plurality of printing units, of a pair of color printing units spaced apart but adjacent and located over one of the first named printing units, means for leading the printed web from one of the first named printing units directly between the two color printing 40 units and out of printing contact with them, and means for leading a web from one of the other printing units through one of the color printing units to print one or more colors on one side of that web. 45

2. The combination with a plurality of units in horizontal alignment, of two color printing units located above and adjacent to them and spaced apart, means for leading a web from one of the first named printing units, after it is 50 printed upon, directly through the space between the two units out of printing contact therewith, and, means for leading two webs from opposite sides, that have been printed upon by other printing units, through the two first named units 55 and printing upon them.

3. The combination with a four color printing unit having two inside adjacent impression cylinders spaced apart, means for leading a web up between the impression cylinders thereof and entirely out of printing contact with both of them, and means for leading another web through one of the color printing units. 60

4. The combination with a plurality of black and white printing units, of two color printing 65 units arranged adjacent to each other above one of the black and white printing units, means for printing on two webs by the color units, means for leading a web from one of said black and white printing units between the two color printing units and entirely out of printing contact with both of them, means for leading another web through one of the color printing units, and means for guiding all four webs adjacent to each other toward a folder. 70

5. The combination with a plurality of black and white printing units, of a pair of color printing units spaced apart but having their impression cylinders located adjacent to each other between their respective printing cylinders, means for leading the printed web from one of said black and white printing units between the two color printing units and entirely out of printing contact with them, means for leading a web from one of the other black and white printing units 10 through one of the color printing units to print one or more colors on one side of the last named web, and means for leading said webs together to a folder.
6. The combination with a plurality of black and white printing units, of two color printing units located adjacent to them and spaced apart with their impression cylinders adjacent, means for leading two webs through two of the black 5 and white printing units and then through the two color units in printing contact therewith, means for leading two webs from the other of said black and white units between said impression cylinders out of contact therewith, and ink 10 motions for the color units on opposite sides of the two color units.

ISIDOR TORNBERG.
